CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a display screen or portion thereof with graphical user interface showing our new design; FIG. 2 shows a second embodiment thereof; and, FIG. 3 shows a third embodiment thereof.

The peripheral dashed broken lines represent a display screen or portion thereof; the peripheral dashed broken lines form no part of the claimed design.
